DESIGN FOR A HAT

Herman Cohn, New York, N. Y.

Application July 3, 1940, Serial No. 93,426

Term of patent 3½ years

To all whom it may concern:

Be it known that I, Herman Cohn, a citizen of the United States, residing in New York city, in the county of New York and State of New York, have invented a new, original, and ornamental Design for a Hat, of which the following is a specification, reference being had to the accompanying drawing, forming part thereof.

Fig. 1 is a front perspective view of a hat showing my design;

Fig. 2 is another view of Fig. 1 illustrating its appearance when contracted.

Fig. 3 is a rear perspective view of Fig. 1, and Fig. 4 is another view of Fig. 3 in its contracted appearance.

I claim:

The ornamental design for a hat, substantially as shown.

HERMAN COHN.
